ELECTRICAL DISTRIBUTION SYSTEM

Herman Gottheimer, Detroit, Mich., assignor to
 Bulldog Electric Products Company, Detroit,
 Mich., a corporation of West Virginia

Application April 5, 1939, Serial No. 266,147

6 Claims. (Cl. 173—334.1)

This application relates to electrical distribution systems of the type employing outlet strips and collectors for use with such strips.

For an understanding of the parts herein disclosed, forming embodiments of such systems, reference should be had to the appended drawing. In the drawing,

Figs. 1 and 2 show different forms of outlet strips in cross section;

Fig. 3 is a fragmentary longitudinal view on line 3—3 of Fig. 1;

Fig. 4 shows the cooperation between a strip and a collector therein.

An electrical distribution system of the type under consideration comprises an outlet strip 15 adapted to receive collectors any place along its length. Generally such systems are not new for systems employing outlet strips and collectors have been well known. Specifically, however, this application discloses modified forms of outlet strips and collectors for such systems.

The outlet strip of Figs. 1 to 4 comprises an elongated ribbon of rubber or the like having its edges folded inwardly to provide a back part 10 and two elongated front parts 11, and there is a slot 12 between the adjacent edges of the front parts. Within the folded ribbon are thin flat bus bars or conductors 14. In the modification of Fig. 1 there are four such conductors, arranged in pairs, so as to be engaged on their meeting faces by the laterally bent portions 16 formed from the prongs 17 of a plug type collector 18 which is associated with the outlet strip by having its portions 16 thrust into the slot 12, and extend longitudinally thereof, whereafter the plug 18 is rotated ninety degrees so that the portions 16 enter the space between the conductors 14 and engage them. In the modification of Fig. 2 but two conductors are employed, one on each side of the slot.

The outlet strip hereof is made of a rubber like material whereby the front parts may be flexed or moved manually, relative to the back parts, to open and widen the spaces between the front and back parts and thus permit the portions 16 of the plugs to enter such spaces and engage the bus bars. The strip and its bus bars are thin enough so as to be coillable on an axis parallel to the back part of the strip and perpendicular to the run thereof.

Now having described the electrical distribution systems herein disclosed, reference should be had to the claims which follow for a determination of the invention hereof.

I claim:

1. An outlet strip comprising an elongated ribbon of rubber or the like having its edges inwardly folded to provide a back part and two front parts, thin flat conductors within the folded ribbon so formed and positioned that their faces are parallel to those of the back part, the outlet strip as a whole, and the conductors particularly, being of so little thickness, measured in a direction perpendicular to the plane of the back part of the strip that the outlet strip can be coiled readily on an axis parallel to its back part and perpendicular to the run thereof.

2. An outlet strip comprising an elongated ribbon of rubber or the like having its edges inwardly folded to provide a back part and two front parts, thin flat conductors within the folded ribbon so formed and positioned that their faces are parallel to those of the back part, the outlet strip as a whole, and the conductors particularly, being of so little thickness, measured in a direction perpendicular to the plane of the back part of the strip that the outlet strip can be coiled readily on an axis parallel to its back part and perpendicular to the run thereof, the edges of the ribbon being in openable sealing relation with the back part of the ribbon to seal the spaces confining the conductors.

3. An outlet strip comprising an elongated ribbon of rubber or the like having its edges inwardly folded to provide a back part and two front parts, thin flat conductors within the folded ribbon so formed and positioned that their faces are parallel to those of the back part, the outlet strip as a whole, and the conductors particularly, being of so little thickness, measured in a direction perpendicular to the plane of the back part of the strip that the outlet strip can be coiled readily on an axis parallel to its back part and perpendicular to the run thereof, the edges of the ribbon being heavily beaded so as to be in openable sealing relation with the back part of the ribbon to seal the spaces confining the conductors.

4. An outlet strip comprising an elongated ribbon of rubber or the like having its edges inwardly folded to provide a back part and two front parts, thin flat conductors within the folded ribbon so formed and positioned that their faces are parallel to those of the back part, the outlet strip as a whole, and the conductors particularly, being of so little thickness, measured in a direction perpendicular to the plane of the back part of the strip that the outlet strip can be coiled readily on an axis parallel to its back part and

perpendicular to the run thereof, the conductors being several in number so that within each of the folds of the ribbon there are two facing conductors.

5. An outlet strip comprising an elongated ribbon of rubber or the like having its edges inwardly folded to provide a back part and two front parts, thin flat conductors within the folded ribbon so formed and positioned that their faces are parallel to those of the back parts, the outlet strip as a whole, and the conductors particularly, being of so little thickness, measured in a direction perpendicular to the plane of the back part of the strip that the outlet strip can be coiled readily on an axis parallel to its back part and perpendicular to the run thereof, the conductors being several in number so that within each of the folds of the ribbon there are two facing conductors, the edges of the ribbon being in openable sealing relation with the back part of the ribbon 20 to seal the spaces confining the conductors.

6. An outlet strip comprising an elongated ribbon of rubber or the like having its edges inwardly folded to provide a back part and two front parts, thin flat conductors within the folded ribbon so formed and positioned that their faces are parallel to those of the back part, the outlet strip as a whole, and the conductors particularly, being of so little thickness, measured in a direction perpendicular to the plane of the back part 10 of the strip that the outlet strip can be coiled readily on an axis parallel to its back part and perpendicular to the run thereof, the conductors being several in number so that within each of the folds of the ribbon there are two facing conductors, the edges of the ribbon being heavily beaded so as to be in openable sealing relation 15 with the back part of the ribbon to seal the spaces confining the conductors.

HERMAN GOTTHEIMER.
